DUST COLLECTING SYSTEM

Lloyd I. Mitchell, New Brunswick, and Alfred W. Meyer, Matawan, N. J., assignors to National Lead Company, New York, N. Y., a corporation of New Jersey

Application July 13, 1950, Serial No. 173,575

1 Claim. (Cl. 183—76)

1
This invention relates to an apparatus for collecting dust or finely-divided materials. More specifically it relates to an improvement in a dust collecting system. More specifically it relates to a method for automatically removing dust from the walls of a collecting device.

One of the problems involved in dust collecting systems is the difficulty in removing particles from the inside walls of the collector as the dust settles thereupon. Many kinds of devices have been proposed and used for many years. Among these devices are included electrical vibrators, knockers, rappers and hammers. When collecting some types of materials, particularly those containing small amounts of moisture or those which inherently possess sticking qualities, such as for example a titanium dioxide pigment, the old methods generally fail to remove all of the dust from the side walls of the apparatus and in addition the vibrators or hammers are inevitably destructive in their action on the apparatus.

An object of this invention therefore is to provide an apparatus wherein dust or finely-divided material may be automatically removed from the walls of a dust collecting system. A further object is to provide an apparatus which will remove slightly moist or inherently sticky material from the walls of a collector. These and other objects will become apparent from the following more complete description of the present invention.

Referring now to the drawing, Figure 1 shows a dust collecting system having a centrifugal collector 10, inlet means 11 connecting the collector to a source of dust laden gas 12 and outlet means for removal of the collected dust 13 and the purged gas 14. The improvements in the dust collecting system comprises flexible inlet connector 15 and flexible outlet connectors 16 to said centrifugal collector; and in addition the novel resilient mounting means such as spring hangers 17. These maintain the collector in substantially vertical position during the operation of the dust collector. In Figure 2 the dust collector is shown in vibrating motion.

The dust laden gas entering the collecting system at relatively high velocity causes vibrations in the collector apparatus. The vibration is maintained by the gas flow because the collector is resiliently mounted and flexibly connected. The vibration of the collector takes place even if the walls of the collector are made of heavier material than that of the connectors themselves, because of the resilient mounting.

2
Preferably however the walls of the collector should be of a material which has sufficient resiliency to permit the walls themselves to vibrate under the conditions of gas flow therethrough.

5 This resilient or thin walled collector is particularly useful for extremely sticky types of materials. It is also to be understood that if the walls of the collector themselves are of a resiliency capable of vibrating under the conditions of gas flow therethrough, the connectors may form an integral part of the collector without resorting to separate flexible connectors.

The flexible connectors shown in Figure 1 are 10 illustrated as bellows-type thin walled metal sleeves. This is an effective type of connector but many other types of flexible connectors may be equally and satisfactorily used.

When this device is used for the collection 15 of finely divided pigments for example it is preferred to have the walls of the collector of a material of a thinness capable of vibrating themselves under the conditions of gas flow therethrough. The gas entering the centrifugal collector sets up a turbulent flow in the collector and the thin walled material and the flexible connections set up a vibration in the entire dust collector which prevents the solid particles from collecting on the inside walls of the container. The solid particles fall to the bottom of the dust collector and are removed 20 through outlet 13. The purged gases are removed through outlet 14 at the top of the dust collector. The dust collector being resiliently mounted sets up a vibration which allows the collection of solid material from dust laden gases 25 to be collected continuously without frequent periodic cleaning of the collector.

On an apparatus requiring insulation it is 30 easier to retain insulation on the outer walls of this type of collector than on other types because of the less destructive nature of the vibration of the collector walls.

The apparatus is easy to install and has substantially low maintenance requirements. It is 35 more satisfactory in preventing build up of finely divided material on the walls of the collector than any of the prior art methods and devices used for this purpose. In addition this apparatus is free from hammers, rappers, knockers and the like, which makes upkeep simple and economical.

While this invention has been described and 40 illustrated by the examples shown, it is not intended to be strictly limited thereto and other modifications and variations may be employed 45 within the scope of the following claim.

We claim:

In a dust collecting system embodying a source of adherent-dust laden gas and including conduit means through which said adherent-dust laden gas is propelled at high velocities, the combination including: a vibratory centrifugal collector for separating said adherent-dust from said gas, said collector having thin metal exterior walls constructed and arranged to be vibrated at high frequencies by entry of said high velocity adherent-dust laden gas into said centrifugal collector, thereby to dislodge the adherent-dust from said metal exterior walls; entry means extending substantially transversely from said centrifugal collector including a bellows sleeve connection arranged to connect said centrifugal collector to said conduit means to deliver said adherent-dust laden gas into said collector; outlet means on said centrifugal collector including flexible connections arranged to remove the separated adherent-dust and the purged gas respectively from said centrifugal collector; and re-

silent hanger means secured to the upper end only of said centrifugal collector and arranged to suspend said collector in a substantially vertical position in space to permit high frequency vibration of said metal exterior walls in directions both longitudinally and transversely of the longitudinal axis of said collector.
